UNITED STATES PATENT OFFICE.

EUGÈNE HENRI TARTRAIS, OF MONTMORENCY, FRANCE.

ROTARY DISTRIBUTER FOR FOUR-CYCLE INTERNAL-COMBUSTION ENGINES.

1,102,817.

Specification of Letters Patent.

Patented July 7, 1914.

Application filed June 15, 1912. Serial No. 703,851.

To all whom it may concern:

Be it known that I, EUGÈNE HENRI TARTRAIS, citizen of the French Republic, and residing at 32 Rue des Chesneaux, Montmorency, Seine-et-Oise, France, have invented certain new and useful Improvements in Rotary Distributers for Four-Cycle Internal-Combustion Engines, of which the following is a specification, reference being had 10 therein to the accompanying drawing.

The distributer valve which forms the subject matter of this invention comprises a continuously rotating cylindrical box arranged within a chamber which is integral 15 with the cylinder and during its rotation successively brings two openings into register with a port in the cylinder. The said openings serve as the inlet and exhaust for the cylinder and communicate with suitable 20 conduits.

Rotary valves which would answer the above definition are already known, but my invention differs from the known devices on account of the arrangement of the various 25 parts, and has the end in view to avoid as far as possible all deformations of the distributer parts by heat, and to reduce the free play of the valve within its chamber to a minimum in order to keep it gas tight, and that without prejudice to the employment 30 of some suitable packing.

My invention is particularly applicable to motors in which four or more cylinders are arranged one beside the other, as is usual 35 upon motor cars. The valve which distributes the gas into all the cylinders is consequently of great length.

The accompanying drawings show by way of example part of a four cylinder motor to 40 which my invention is applied.

Figure 1 is a section through the motor, perpendicular to the cylinders and passing through the axis of the distributer; Fig. 2 is a section through the end cylinder perpendicular to the axis of the distributer. Fig. 3 is a section on the line A—B of Fig. 1, through the distributer. Fig. 4 is a section showing the distributer with its water jacket made with integral walls. Fig. 5 shows a 50 modified form of the distributer.

The distributer proper 1 rotates continuously around its axis, in the direction of the arrow 2 for example, within its chamber 3 which is formed in the cylinder casting. 55 The distributer has two conduits, a central conduit 4 for the exhaust and an annular

conduit 5 for the inlet of the mixture. These conduits are alternately brought into communication with the cylinders 6₁, 6₂, 6₃, 6₄ by means of the openings 7₁, 7₂, 7₃, 7₄ and 8₁, 8₂, 8₃, 8₄ in the distributer, coming into register with the ports 9₁, 9₂, 9₃, 9₄ of the cylinders at the requisite moments and thus allowing the exhaust of the gases through the conduit 4 which terminates into the pipe 10. The 60 inlet is through the conduit 5 which is in communication with a carburetor (not shown) by a pipe 11 and space 12 in the distributer. Within the distributer a heat 65 resisting lining 13 is provided and may consist for example, of asbestos protected by a metallic cover. The outer wall of the valve is formed of two sleeves 14 and 14', which are attached to the inner wall of the valve at one of their respective ends. One of these 70 sleeves is provided with the bosses or enlargements 16 which receive the screws 17 which pass through the other sleeve, as seen clearly in Figs. 1 and 5. A shaft 18 imparts motion to the distributer by an interposed 75 Oldham coupling 19.

As above stated, the object of the described arrangement is mainly to produce a minimum deformation of the distributer parts, and the manner in which this result is 80 obtained is as follows: According to my invention the exhaust pipe 10 terminates in a space by which minimum contact of the exhaust gases with the parts of the distributer is effected and thus a minimum heating of 85 the same occurs.

The concentric arrangement of the conduits, with the inlet around the exhaust permits of maximum contact of the combustible mixture with the parts of the distributer, 90 thus effecting a maximum cooling. The heat resisting lining largely prevents the heating of the exhaust conduit and because of this, also the heating of the combustible mixture and of the walls of the distributer 100 which otherwise would take place through radiation, convection and at certain points through conduction. Most of the deformations of the exhaust conduit are thus prevented, which is of very great importance 105 because such deformations, when they take place tend to lift the valve or the distributer at the places of contact where gas-tightness is desired. Moreover, assuming the case of a distributer consisting of one piece; the expansion of the sockets 20 in the direction of the arrows 21 tends to deform the distrib- 110

uter as it is indicated by exaggerated dotted lines 22 in Fig. 4.

It is to be noted that by the construction hereinbefore described the distributor is prevented from getting unduly heated and thus proper lubrication assured. The preservation of the gas in a fresh condition, attained particularly by the heat resisting lining, is also very advantageous.

10 The various parts of the distributor can be taken apart and this permits of easy cleaning and avoids accidents which may arise by particles of metal coming between the distributor and its chamber while working.

15 This description and the annexed drawings only show an example of carrying out my invention and I may vary the same to suit requirements. Instead of one space or 20 interval 12 I may arrange two, or even more, according to the number of cylinders. In the described example, the intermediate annular sleeves are fixed at one extremity but they may be fixed in their center as shown 25 in Fig. 5, for example, in which figure the like parts have like reference letters as in Figs. 1 to 4.

Having now described my invention what 30 I claim and desire to secure by Letters Patent is:—

In a valve for multiple cylinder internal combustion engines, a cylindrical casing provided with a series of ports communicating with the cylinders of the engine, said casing being further provided with an annular inlet channel in communication with an inlet passage, a cylindrical member revolvable in said casing and provided with a port in constant communication with said channel and with inlet and outlet ports arranged 40 for successive communication with the first series of ports, a second cylindrical member, said members being attached at their respective ends to provide an annular inlet passage, said second member having extensions forming ports communicating with the outlet ports of the first member, and a third cylindrical member within the second member, said third member forming heat nonconductor and fire proof lining and having ports adapted for communication with the ports of the second member, and an exhaust passage in constant communication with said third member.

50 In testimony whereof I affix my signature in the presence of two witnesses.

EUGÈNE HENRI TARTRAIS.
